CLAIM

The ornamental design for a flame container, as shown and described.

DESCRIPTION

FIG. 1 is a perspective view of a flame container showing our new design.

FIG. 2 is a front elevation view;

FIG. 3 is a left side view elevation view;

FIG. 4 is a top plan view;

FIG. 5 is a bottom plan view;

FIG. 6 is a perspective view of an alternate embodiment of a flame container showing our new design.

FIG. 7 is a front elevation view;

FIG. 8 is a left side view elevation view;

FIG. 9 is a top plan view;

FIG. 10 is a bottom plan view;

FIG. 11 is a perspective view of another alternate embodiment of a flame container showing our new design.

FIG. 12 is a front elevation view;

FIG. 13 is a left side view elevation view;

FIG. 14 is a top plan view;

FIG. 15 is a bottom plan view;

FIG. 16 is a perspective view of another alternate embodiment of a flame container showing our new design.

FIG. 17 is a front elevation view;

FIG. 18 is a left side view elevation view;

FIG. 19 is a top plan view; and,

FIG. 20 is a bottom plan view.
